APPARATUS FOR PRODUCING COILS OF
NARROW STRIP FED THERETO FROM
A SLITTERHjalmer A. Ray, Fairhaven, Mass., assignor to
Revere Copper and Brass Incorporated, New
York, N. Y., a corporation of Maryland

Application January 17, 1950, Serial No. 138,965

5 Claims. (Cl. 242—78)

1

My invention relates to forming tied or bound coils of narrow strip utilizing a slitter which divides a relatively wide strip into a plurality of narrow strips.

The invention, which has among its objects an improved apparatus for forming such coils with a minimum of labor on the part of the workmen and with an increased output of coils in a given time, will be best understood from the following description when read in the light of the accompanying drawings, while the scope of the invention will be more particularly pointed out in the appended claims.

In the drawings:

Fig. 1 is a plan of a form of apparatus according to the invention;

Fig. 2 is an elevation of the apparatus according to Fig. 1;

Fig. 3 is an elevation, with parts broken away, illustrating a step in the operation of forming the coils;

Fig. 4 is an elevation, with parts in section, illustrating a further step in the operation of forming the coils;

Fig. 5 is a plan illustrating a still further step in the operation of forming the coils; and

Fig. 6 is a perspective view illustrating one of the completed coils.

It is frequently necessary to divide a wide strip, of brass or the like, longitudinally into a number of narrow strips, for example, a strip 20 inches wide into 80 strips each $\frac{1}{4}$ inch wide. This is done by passing the wide strip longitudinally through a so-called slitter. Such a slitter, which is a well known device, is more or less diagrammatically illustrated in Figs. 1 and 2 of the drawings. As shown in those figures, it comprises a standard 1 carrying the spaced housings 3 each formed with a so-called window 5 in which are mounted the bearings 7 for the opposite end portions of the driven rotary arbors 9, the upper bearings being vertically adjustable manually by means of the screws 11 which carry the hand-wheels 13 at their upper ends. Each arbor 9 fixedly carries a plurality of circular flat disk-like cutters 15 separated by spacers 17, the cutters on the upper arbor being staggered with relation to those on the lower arbor so that the cutters on the upper arbor are aligned with the spaces between the cutters on the lower arbor to shear a relatively wide strip S into a plurality of narrow strips N when the former is passed between the cutters on the two rotating arbors. If the narrow strips, for example, are to be $\frac{1}{4}$ inch wide the cutters will be $\frac{1}{4}$ inch wide and spaced $\frac{1}{4}$ inch apart.

2

Heretofore the narrow strips while being discharged from the slitter have been coiled on a horizontal rotary blocker having a free unsupported end, all the strips being simultaneously wound on one and the same blocker with flat disk-like spacers placed on the blocker between the strips so that the coils will be wound in the spaces between the spacers. According to this prior practice, at the end of the winding operation the pancake coils thus formed are axially slid manually one by one off the blocker at its free end and the turns of the coils tied or bound together. To remove each coil from the blocker it is necessary, according to prior practice, for the workman, while each coil is still on it, to sever the end of the outer turn of the coil from the residual length of narrow strip leading to the slitter and hold the severed end of the coil to prevent the latter from unwinding, which it would do, like a clock spring, if its outer end were released. The operator while holding the outer end of the strip and the adjacent peripheral portion of the coil with one hand then grasps the diametrically opposite peripheral edge portion of the coil with his other hand, and by use of both hands pulls the coil off the blocker. When pulled off the blocker he carries the coil to the table on which he lays it flatwise and, while still holding the coil against unwinding, a second operator ties or binds the turns of the coil together so that there is produced a pancake coil 19 (Fig. 6) tied or bound at three places by means of the wires or cords 21. To get the cord or wire about the coil the latter is slid partly over the edge of the table so as to enable the cord or wire to be passed through the center opening of the coil, the latter being rotated while supported by the table to enable the three cords of wires to be applied.

Great difficulty is experienced by the workman in performing the above operation in respect to preventing the coil turns from telescoping while he pulls the coil from the blocker and carries it to the table. Ordinarily while carrying the coil he holds it flatwise against the front of his body to prevent such telescoping, and in working the coil off the blocker he must do it very slowly and carefully to prevent its telescoping. This difficulty will be appreciated when it is considered that the coil of narrow strip may weigh as much as ninety pounds and may be 36 inches in diameter. The operation in fact is so laborious that it physically exhausts the workman. Another defect of this old procedure is that it ties up the slitter while the coils are being slowly removed from the blocker.

According to the improved apparatus, there are provided two rigid disk-like members 23 each comprising an annular metal plate 25 to one side of which adjacent its outer periphery is welded one web 27 of an angle-iron 29 bent to form a ring, the other web 31 of the angle-iron forming means for attachment of the hooks 33 (Fig. 3) of a sling 35 carried by the hook 37 of a bodily movable hoist (not shown). On the same side of each plate 25 as the angle-iron ring 29 is welded the edge of a ring-shaped flange 39 adapted to fit over the blocker, this ring being tapped for receiving a set screw 41 for securing the member 23 non-rotatably to the blocker when desired. As further shown, the members 23 adjacent their peripheries are each formed with three equally spaced perforations 43 for removably receiving the tie rods 45. As shown, the tie rods have at one end the heads 47, and at their ends opposite the heads are screw-threaded, as shown at 49, for removably receiving the clamping wing nuts 51, which latter are adapted to draw the members 23 toward each other for clamping the coils between them as hereinafter explained. The perforations 43 are shown as positioned close to the peripheral webs 31 of the angle-irons 29, and the heads of the tie rods preferably rigidly carry radially projecting pins 53 adapted to abut with said webs to prevent rotation of the tie rods when the clamping nuts 51 are being screw-threaded on said rods.

The blocker shown is one of common construction, comprising a power driven cylindrical member 55 having a free unsupported end 57. The cylindrical outer surface portion of the member 55 comprises two segmental members 59 (Fig. 2) which extend for the full length of the member 55, these members 59 being so mounted that at one end each bears against an elongated abutment 61, also extending for the full length of the member 55, about which end it may be swung to render the member 55 radially expansible and contractible for releasably clamping to it the ring-shaped flanges 39 of the rigid members 23 when the latter are placed on the blocker. The member 55 is so expanded and contracted by applying to the nut 63, positioned at the free end of the member, a wrench for rotating the nut, the nut operating known mechanism housed by the blocker for imparting the swinging movements to the members 59. As further shown, one of the members 59 is provided with a projection 65 in which is formed a groove 67, the groove extending for the full length of the member 55 and opening at one edge on the outer surface of such member and endwise on the free end of the blocker.

In setting up the improved apparatus the end of the wide strip S leading from a coil of the same is applied to the slitter and the latter operated to form lengths of narrow strip sufficient to reach to the blocker, whereupon operation of the slitter is temporarily discontinued. As shown, these preliminary lengths of narrow strip, indicated at P in Fig. 2, are conveniently supported on a table 69 extending across the space between the slitter and the blocker. At this stage of the operation the blocker is collapsed sufficiently to permit one of the rigid members 23 to be placed on it, and after it is so placed the end of the adjacent narrow strip is secured to the blocker by bending such end and inserting it in the groove or slot 67. Then a thin annular disk-like spacer 71 (Figs. 4 and 5), preferably of sheet metal, is placed on the blocker

and pushed up against the strip, causing the latter to be pushed into contact with the rigid member 23. The central opening 73 (Fig. 5) of the spacer, which permits it to be placed on the blocker, is preferably of such diameter that it fairly closely fits the blocker when the latter is expanded to clamp the rigid members 23 thereto, but with sufficient clearance not to interfere with such clamping. Next the end of the second strip 10 is secured in the same way to the blocker and a second spacer 71 positioned on the blocker and pushed up against that strip. Finally after all the strips are secured to the blocker with spacers positioned between them the second rigid member 15 23 is placed on the blocker and the latter expanded to secure both rigid members thereto. When the first rigid member 23 is placed on the blocker the set screw 41 (Fig. 4) preferably is screwed up against the abutment 61 of the blocker to prevent that member from rotating relative to the blocker, and when the second member 23 is placed on the blocker the perforations 43 of the two members are aligned by rotating the last positioned member and temporary use of one of the tie rods 45, whereupon they are kept in alignment by tightening up against the abutment 61 the set screw 41 on the second member preparatory to firmly clamping both members to the blocker by expanding the latter. The slitter is 20 now again put into operation and the blocker rotated until the coils are formed, these operations being discontinued as heretofore while a short length of the wide strip still remains unslit so as to hold the coils at this point of the operations from unwinding.

When the above operations are completed the tie rods 45 are inserted through the perforations 43 and the nuts 51 applied to the tie rods. Then the outer ends of the strips forming the coils are 25 snipped one by one from the lengths of strip leading to the slitter, and as soon as each is snipped its end leading to the coil is bent to hook it about one of the tie rods, as indicated at 75 (Fig. 5), to prevent the coil from unwinding, the ends of all of the coils being secured to the same tie rod. The blocker may then be collapsed and the set screws 41 backed off to release the rigid members 23 from the blocker, whereupon the wing nuts are tightly screwed up by use of a wrench to draw each rigid member 23 toward the other and firmly clamp the coils and spacers between them. The webs 31 of the two rigid members are now caused to be engaged by the hooks 33 of the hoist, as shown in Fig. 3. By moving the hoist the assembly, consisting of the rigid member 23, coils 19, tie rods 45, wing nuts 51 and spacers 71, may then be slid off the blocker and transported to the skid 77 shown in Fig. 4, the assembly being laid flatwise on the elongated blocks 79 carried by the skid. The tie rods 45 are so applied that when the assembly is on the blocker two of the wing nuts 51 will be positioned at one end of said assembly and the third wing nut at its opposite end, the outer ends of the strips coming from the coils being secured to the tie rod associated with this third wing nut, while the assembly is so placed on the blocks 79 that this third wing nut will lie at the top of the assembly. When the assembly is placed on the blocks 79 the three wing nuts may then be removed and the upper rigid member 23 lifted from the assembly, which will remove with it two of the tie rods but leave in place the third to which the coil ends are attached. The uppermost 30 coil of the assembly may then be slid sidewise

and turned on the adjacent spacer 71, as indicated in Fig. 5, to permit the tie or binding cords or wires 24 to be applied one by one, after which the end of that coil secured to the tie rod may be snipped off, whereupon this top coil may be removed from the assembly. The spacer, on which the top coil rested, may then be removed to expose the next coil at the top of the assembly, which last mentioned coil may then be tied or bound by cords or wires 24, its end attached to the tie rod snipped off, and the coil removed. In this way all the coils may be tied or bound and removed.

Use of the improved apparatus avoids all the labor and difficulty of the above described prior method, and further does not tie up the slitter while the coils are being tied or bound, for as soon as the assembly is removed from the blocker another set of rigid members 23 and spacers 71 may be employed for permitting the slitting and winding operations to be resumed by use of the remainder of the same wide strip S or by use of a new wide strip S.

It will be understood that within the scope of the appended claims wide deviations may be made from the form of the apparatus shown without departing from the spirit of the invention.

I claim:

1. Apparatus for forming coils of narrow metal strip fed longitudinally to said apparatus from a slitter for dividing an elongated wide metal strip longitudinally into a number of simultaneously formed elongated narrow strips, which apparatus comprises a rotary blocker for winding such narrow strips simultaneously into pancake coils simultaneously with their being formed, which blocker has a free end and has means adapted releasably to secure the ends of said strips thereto for effecting such winding and to permit detachment of said ends therefrom for permitting such coils to be slid from said blocker over said free end, thin spacing disks having openings adapting them to be carried by said blocker between said coils, rigid members having openings adapting them to be carried by said blocker at opposite ends of the group of coils wound thereon, releasable members adapted to secure said rigid members to each other after the coils are wound for clamping the coils between them, at least one of which releasable members provides means for attachment of the outer free ends of the coils thereto for preventing unwinding of such coils, whereby one of said rigid members may be placed on said blocker and the ends of the narrow strips coming from the slitter may be successively secured to said blocker with the spacing disks placed on the blocker between them and then the other rigid member may be placed on the blocker and the narrow strips wound into coils, and, upon completion of the winding operation, the rigid members may be secured to each other by said releasable members and the outer ends of the coils secured to one of said releasable members to form an assembly which may be removed as a unit from the blocker, and the coils may be successively removed from said assembly and bound by supporting the assembly with its axis disposed vertically and, after removing all said releasable members except the one to which the outer ends of the coils are secured, by successively sliding the coils flatwise one by one from the spacing disk beneath it and binding it while on said spacing disk and while

the outer end of the coil is secured to such releasable member.

5 2. Apparatus according to claim 1 in which the blocker is radially expansible and contractible, the rigid members being in the form of disks having openings provided with peripheral flanges adapted to fit over the blocker, the releasable securing members being in the form of removable tie rods adapted to be positioned at the outer sides of the coils after the latter are wound and to extend through openings in the rigid members, whereby said openings may be placed in alignment prior to the winding operation and by expanding the blocker for clamping said flanges thereto may be kept in alignment to permit insertion of the tie rods through said openings after the winding operation is completed.

15 3. Apparatus according to claim 1 in which the blocker is formed with a longitudinal groove opening laterally on the outer surface of the blocker for permitting insertion of the ends of the strips coming from the slitter for securing said ends to the blocker and opening on the free end of the blocker for permitting the coils to be slid axially off it over its free end.

20 4. Apparatus according to claim 1 in which the blocker is formed with a longitudinal groove opening laterally on the outer surface of the blocker for permitting insertion of the ends of the strips coming from the slitter for securing said ends to the blocker and opening on the free end of the blocker for permitting the coils to be slid axially off it over its free end, the rigid members having provision for releasable attachment to a hoist for supporting the assembly when being moved off the blocker to so slide such coils.

25 5. Apparatus according to claim 1 in which the blocker is formed with a longitudinal groove opening laterally on the outer surface of the blocker for permitting insertion of the ends of the strips coming from the slitter for securing said ends to the blocker and opening on the free end of the blocker for permitting the coils to be slid axially off it over its free end, the rigid members having provision for releasable attachment to a hoist for supporting the assembly when being moved off the blocker to so slide such coils, the blocker being radially expansible and contractible, the rigid members having openings provided with peripheral flanges adapted to fit over the blocker, the releasable securing members being in the form of removable tie rods adapted to be positioned at the outer sides of the coils after the latter are wound and to extend through openings in the rigid members, whereby said openings may be placed in alignment prior to the winding operation and by expanding the blocker for clamping said flanges thereto may be kept in alignment to permit insertion of the tie rods through said openings after the winding operation is completed.
